SNAP CLAMP OR GRIP FOR ELECTRICAL CONDUCTORS.

1,172,601.

Specification of Letters Patent. Patented Feb. 22, 1916.

Application filed February 18, 1914. Serial No. 819,360.

To all whom it may concern:

Be it known that I, TOMLINSON FORT JOHNSON, Jr., a citizen of the United States, and a resident of Atlanta, in the county of Fulton and State of Georgia, have invented certain new and useful Improvements in Snap Clamps or Grips for Electrical Conductors, of which the following is a specification.

10 This invention relates to a snap clamp or grip for electrical conductors and cables, particularly bare conductors of the overhead type as used on transmission lines which go cross country for considerable 15 distances, and which are exposed to storms, snow, sleet and unfavorable conditions.

Among the numerous uses of this improved snap clamp or grip, the following conditions of practice may be mentioned.

20 The connection of a bank of transformers or services at any point of the line has hitherto required a more or less permanent type of connection to the transformers, at the place desired, the installing or repairing 25 of which interrupts the service to all the other customers along the line. This connection can be made with the present snap clamp without interrupting the service.

When a workman is repairing the line at 30 any point, he is required to take the precaution of grounding the line to avoid the danger of being killed by a misunderstanding at the power station. The snap clamp or grip of the present invention finds an 35 important use for making such ground connection. Also it is frequently desirable to connect one line to another, the two being advantageously used in multiple for a certain period, and by the snap clamp or grip

40 in the present invention, such connection of the two lines in multiple may be made without shutting down the service on either line to make the cut-in. Also the snap clamp or grip in the present invention has an important feature in use as a substitute for pole disconnecting switches, and for sectionizing lines, and for various uses as jumpers between conductors and other purposes as will be later pointed out.

50 In the drawings:—Figure 1 is a side elevation of a snap clamp or grip embodying the principles of this invention. Fig. 2 is a front elevation of the same, and Fig. 3 is a rear elevation.

55 Constructions embodying the invention

will include a pair of jaws 1 and 2, with a V entrance 3, the V entrance of the jaws opening into a transverse passage 4 between the jaws which is adapted to be very tightly gripped or clamped upon the usual circular 60 bare conductor 5 of a transmission or other line.

In the best constructions embodying the invention the jaw 1 is made the terminal of a flexible conductor 6, which is preferably 65 socketed into this jaw and held by a set screw 7. A soldered or brazed joint may be used. For the purpose of strength a somewhat enlarged lug or base 8 is formed on the lower portion of this jaw 1, with a 70 flat face 9 at a convenient angle on one side, which lug or base is drilled and tapped for the set screw 7 which impinges on the flexible conductor 6. This jaw 1 may, for the purposes of convenient definition, be termed 75 the loop carrying jaw, as it receives the flexible stranded or flat conductor 6 which may be a loop to another clamp. This 80 flexible or other conductor is not always joined to another clamp, however, as it is useful for grounding transmission wires or the like, and by the term loop, it is not desired to confine the invention to use of an actual loop between two separate clamps.

The loop carrying jaw 1 has a yielding or 85 pivotal connection with the other jaw, which is thereby relatively movable with respect to the loop carrying jaw. In addition to being relatively movable the two jaws are furthermore designed to be gripped 90 toward one another so as to tightly grip upon a conductor wire.

In the construction illustrated in the drawings, the loop carrying jaw 1 has studs 12 rigidly projecting therefrom, which extend loosely through holes 13 in the relatively movable jaw 2, which studs 12 are surrounded by comparatively small coil springs 14 bearing on the relatively movable jaw, and against the fixed anchorage afforded by the heads 15 of the studs. The studs are most conveniently formed of simple machine screws threaded into the loop carrying jaw, and having lock nuts 16 securing them rigidly in place. Washers 17 interposed between the ends of the springs and the jaw 2 and stud heads 15, will ordinarily be provided to better permit movement of the springs. It will be evident that these springs keep the relatively movable jaw al- 100 105 110

ways yieldingly pressed toward the loop carrying jaw. This fact is utilized in establishing a very simple pivotal connection between the two jaws consisting of a mere 5 rounded bead 20 at the upper end of the relatively movable jaw which is received in a corresponding groove 21 at the upper end of the loop carrying jaw. The foreclosure of the springs 14 makes this pivot as effective 10 as any kind of pivot, and it is more durable, and cheaper to construct than a hinge or the like. The proper position of the studs 12 and springs 14 is at about the middle of the jaw 2, and also, preferably, 15 closely adjacent to the groove 4. Both jaws are best transversely grooved to receive the transmission conductor. The form of the grooves may vary to suit different wires and shape of conductors. But for the ordinarily 20 round solid conductor, grooves with four plane faces are preferred, gripping the wire 5 on four zones substantially 90 degrees apart by a wedging or diagonal action which gives a maximum current carrying capacity 25 at each zone. The current carrying capacity of each zone is multiplied by four for the whole clamp in view of the four zone engagements of the four faces on the circular conductor wire. The advantage of this 30 engagement as to current carrying capacity is manifest.

It is, of course, to be constantly borne in mind that the whole effectiveness of the clamp is dependent on its current carrying 35 capacity, since without high current carrying capacity any attachment is obviously worse than useless, being wasteful, totally unreliable, and exceedingly dangerous. In this connection the strong spiral springs 14 40 have an important effect in insuring a good electrical contact, as does also the location of the studs and springs in close proximity to the transverse grooves 4, so that they have a direct action. The V entrance to the jaws 45 will be of substantial size, opening outward into a fairly considerable separation, so as to permit easy manipulation. Both jaws are preferably cast, the relatively movable jaw 2 having a rib 22 along the back, in the best 50 constructions, which by running from tip to tip of the relatively removable jaw in a substantially straight line gives the maximum strength and maximum lightness, and also compactness.

55 The further features of the invention relate to the manipulation of the clamp by which it is easily attached to and detached from the transmission wires. Near the upper end of one of the jaws, preferably near 60 the top of the loop carrying jaw 1, an eye 23, or equivalent projecting lug is formed, preferably by an integral rib at this point, drilled with a comparatively large hole. At the lower end of the clamp and preferably 65 on the same jaw, another hook or lug 24 or

the like is formed, also preferably integral. I prefer a simple upstanding cast hook 24 on the lower part of the loop carrying jaw. With this construction the device can be easily manipulated by anyone under any circumstances, it being merely necessary to take a pole, lift the snap grip into the air by the eye 23 and poise it over the conductor 5, on which a connection or tap is desired. The device is then lowered until the V jaws 70 pass over the conductor, after which the pull of a pole on the lower hook 24 snaps or grips the conductor into the V of the jaws and into the transverse conductor receiving groove 4. To disengage the clamp it is 80 merely necessary to hook the end of the pole into the eye 23 and pull downward, whereupon the snap clamp flips upside down and is in a position to be pulled directly off the conductor as shown in Fig. 3. It is evident that this manipulation is equally easy, whether the transmission wire is carrying current or otherwise. In fact the line may be charged to eleven thousand or fifty-five thousand volts, or almost any voltage without danger to the workman who does all the manipulation through a long pole comparatively distantly removed from the charged conductor. Of course, the pole may have a hook or pin or stud or any similar 95 projection at the top to more conveniently engage the eye and hook in an obvious manner.

The device will ordinarily be used with two snap clamps connected at the ends of an intermediate loop conductor, so that the pair may be snapped between two conductors for any purpose, as for example, any of the purposes referred to in the preamble of the specification. Its convenience 100 of attachment and particularly its current carrying capacity make it particularly adapted for use as a connection between two conductors, one for tapping in transformers or banks of transformers for new or temporary customers on a line without interrupting the service of other customers and also for temporarily or permanently connecting two lines in multiple or for dead ending the line, or grounding the line.

In general the clamp may be used almost anywhere in this class of service, since its current carrying capacity is high enough to be relied upon under all conditions, and the device is therefore as serviceable as any 115 form of tap connection which can be made. On the other hand the quickness with which it may be attached and detached, and particularly its ability to be manipulated by a pole, out of any zone of danger, makes it 120 possible of use throughout its whole range of service without interrupting the power on the line, which is always a matter of trouble and inconvenience, and which interferes with the service. The snap clamp 130

- of the present invention makes it possible to provide for practically all conditions without interrupting the service and to make connections with this clamp in place of using a soldered permanent connection which has substantially no greater current carrying capacity or durability in its favor to warrant the extra cost, trouble, inconvenience, danger and delay.
- 10 Instead of jaws of cast metal, sheet metal jaws may be used, and in this case substantially the same form may be given to the complete clamp by suitably shaping and embossing the metal. For example, the 15 relatively movable jaw may be made with V shaped longitudinal and lateral corrugations intersecting like a cross, the transverse groove being for the conductor 5, while the longitudinal groove gives stiffness like the 20 rib 22 of the first construction. The loop carrying jaw may have a riveted on hook on the bottom and a riveted on eye at the top, both hook and eye having an L shape or T shape in transverse section so as to afford a 25 base suitable for riveting to the body of this jaw. The T shape may be given by bending one ear in one direction, and another ear in another direction, or may be made by having two thicknesses of sheet metal with 30 separate ears bent in opposite directions. The pivot connection between the jaws is readily provided by turning up over a pair of ears or lugs at the upper end of the loop carrying jaw, and similarly carrying to one side an intermediate lug or lugs on the relatively movable jaw, which will coöperate in an obvious way with the lugs of the loop carrying jaw to form sort of a hinge or 35 pivot connection, held together by the force
- of the springs as in the first described construction.
- Ribs may be formed wherever desired to give adequate stiffness, for example at the ends of the transverse bent channel for the conductor 5. It is evident that this construction is cheaper to make in large quantities than the cast metal form.

What is claimed is:—

1. A grip for electric conductors comprising a pair of rigid jaws with a V entrance between, each jaw having a transverse groove, a stud projecting from one jaw, a spring on said stud for closing the jaws together, a projection on one of the jaws for lifting and lowering the device into engagement with an overhead conductor, and means on one of the jaws for the attachment of a cable thereto.
2. A grip for electric conductors comprising a pair of jaws with a V entrance between them, grooves on the jaws to bite upon the conductor, a bead and groove engagement between the jaws constituting a hinge, a spring between said hinge and said first mentioned grooves, a projection on one of the jaws for lifting and lowering them into engagement with an overhead conductor, a projection to permit the jaws to be forcibly pulled or drawn down over a conductor, and an enlargement on one of the jaws to which a cable is connected.

Signed at Atlanta in the county of Fulton and State of Georgia this 11th day of February A. D. 1914.
